US00D951632S

(12) **United States Design Patent** (10) Patent No.: **US D951,632 S**
(45) Date of Patent: **** May 17, 2022**

(54) **WALLET**

(71) Applicants: **Thuan Tran**, Santa Clara, CA (US);
Charlie Carroll, Palo Alto, CA (US);
Binh Tran, Santa Clara, CA (US)

(72) Inventors: **Thuan Tran**, Santa Clara, CA (US);
Charlie Carroll, Palo Alto, CA (US);
Binh Tran, Santa Clara, CA (US)

(73) Assignee: **Dango Products, LLC**, Portola Valley,
CA (US)

(**) Term: **15 Years**

(21) Appl. No.: **29/754,200**

(22) Filed: **Oct. 7, 2020**

(51) LOC (13) Cl. **03-01**

(52) U.S. Cl.

USPC **D3/247**

(58) **Field of Classification Search**

USPC D3/247, 249-253; D8/16, 19, 105;
D11/78.1
CPC ... A45C 1/06; A45C 11/182; A45C 2001/065;
A45C 2001/067

See application file for complete search history.
